(57) **CLAIM**

The ornamental design for a docking station for a removable camera screen, as shown and described.

DESCRIPTION

FIG. 1 is a front and left side perspective view of a docking station for a removable camera screen showing my new design;

FIG. 2 is front elevational view thereof;

FIG. 3 is rear elevational view thereof;

FIG. 4 is a left side elevational view thereof;

FIG. 5 is a top plan view thereof; and,

FIG. 6 is bottom plan view thereof.

The portions of the docking station in broken lines are shown for illustrative purposes only and form no part of the claimed design.
